UNITED STATES PATENT OFFICE.

HUGH B. BROCKENBROUGH, OF FORT DODGE, IOWA.

CABLE CONNECTION FOR TRAMWAY-CARS.

1,242,915.

Specification of Letters Patent. Patented Oct. 16, 1917.

Application filed June 12, 1916. Serial No. 103,196.

To all whom it may concern:

Be it known that I, HUGH B. BROCKENBROUGH, a citizen of the United States, and a resident of Fort Dodge, in the county 5 of Webster and State of Iowa, have invented certain new and useful Improvements in Cable Connections for Tramway-Cars, of which the following is a specification.

10 My invention relates to improved connecting means particularly adapted for connecting tramway cars with cables. Although my invention is applicable in surface tramways it is particularly adaptable in aerial tramways, such as tramways 15 constructed between a loading and unloading station for receiving and dumping merchandise, such as ore. Such systems usually comprise two parallel tracks suspended 20 closely together with provision made for connecting the ends so that the cars can run continuously around the circuit in one direction on one track and in the opposite direction on the other. The ends of the 25 tracks could, of course, be connected together by curves but in order to rotate the car trucks the cars would have to be of considerable radius. This is, of course, impractical as it would require considerable 30 and expensive supporting framework and expensive cable arrangement at the curves, particularly in the nature of cable sheaves and supports. I provide simplified mechanism for shifting a car from the end of one 35 track to the adjacent end of the other track, the arrangement being such that only a single sheave is necessary at each end for guiding the cable from one track to the other. The arrangement involves a supporting 40 frame adapted to shift transversely across the main track ends, the frame supporting a platform having rails normally in line with one track to receive a car, the tracks being carried with the car and frame in 45 registration with the other track, the car being always parallel with the main tracks and traveling bodily around the cable sheave.

50 My invention concerns particularly the connection between a car and the cable which can readily follow the cable around the track end sheaves without causing binding, the connection being also such as will readily pass through the cable driving mechanism. Generally speaking, my improved connection 55 comprises a clamp to which the cable is rigidly and permanently secured and

which can rotate about a vertical pivot and which can swing about a horizontal pivot so as to adapt itself to various curves and positions it must take when passing around the track end sheaves with the car which remains always parallel with the tracks. 60

On the accompanying drawing the details of construction and operation of my invention are clearly shown. In these drawings— 65

Figure 1 is a plan view showing the car shifting mechanism at one end of the tracks,

Fig. 2 is a view from plane 2—2, Fig. 1,

Fig. 3 is an enlarged side elevational view of the cable connection above the connector 70 between the car and cable,

Fig. 4 is an end view of the connector showing its position when it is traveling around a sheave, and

Fig. 5 is a sectional view on plane 5—5, 75 Fig. 3.

Describing first the arrangement for which my improved connector is particularly adaptable, in Fig. 1 the car shifting frame F comprises side beams 10 connected 80 by cross beams 11, the beams 10 riding on rollers 12 mounted at the tops of posts 13. The beams 10 extend transversely of the ends of parallel tracks T and T' which form part of an aerial railway. Supported on 85 brackets 14 suspended from the beams 10 are the track rails 15. These rails travel with the car shifting frame to be carried into registration with the tracks T and T', a weight 16 on the cable 17 passing through 90 sheave 18 tending to hold the frame with the rails 15 in registration with the rails of track T so as to receive a car coming toward the frame on track T. Below the track 15 the horizontal sheave 19 is journaled in the 95 vertical bearing frame 20 secured to the railway supporting structure 21, the axis of the wheel being midway between the tracks T and T'. There is a sheave at each end of the main tracks T and T' and about 100 these sheaves passes a cable 22, the cable, at some point between these sheaves, being engaged by cable driving mechanism (not shown). The sheaves are of such diameter that the cable lines pass between the rails 105 of the tracks T and T' in order that cars C may be connected to the cable. Usually connection is made with the under side of the cars. With the car shifting arrangement shown in Figs. 1 and 2 a car is propelled by the cable from track T onto the rails 15 of the shifting frame and then the

110

car will have a combined longitudinal movement along rails 15 and lateral movement with the shifting frame until the rails 15 are brought into registration with the track T' whereupon the car enters the track T', the car always remaining parallel with the tracks T and T'.

The cable connection between the cable and car must be such that it can readily coöperate with the groove of the cable sheave during shifting of the car from one track to the other. In Figs. 3, 4 and 5 is shown my improved connector which is particularly adaptable for shifting arrangement such as shown in Figs. 1 and 2. In this connector 23 represents a plate having a cylindrical stud 24 extending vertically upwardly therefrom to pass through the floor of the car C and to be engaged by a nut 25. With this arrangement the plate 23 is free to rotate about the axis of the stud 24. Depending from opposite sides of the plate 23 are the legs 26 through whose ends passes the horizontal pivot bolt 27 secured by nut 28. This bolt also receives the up-standing ears 29 and 30 on a block or plate 31 which is received between the upper ends of a sheet metal strap or frame 32 of U-shaped cross-section, the strap being secured by bolts 33. The cable 22 engages in the bend or bottom of the frame 32 and is securely clamped therein in any suitable manner. As shown, wedge mechanism is used, a wedge block 34 passing through the frame between the lower wedge surface 35 of block 31 and the upper wedge surface 36 of the block 37 engaging the cable 22. The wedge block 34 has the threaded stud 38 extending from its apex end beyond the edges of the frame 32 and a nut 39 engaging this stud abuts against the frame edges when turned and the cam block is drawn against the wedge surfaces 35 and 36 to securely force and press the block 37 against the cable to thus clamp the cable rigidly in the bend of the frame 32.

The connector described can rotate about a vertical axis and swing about a horizontal axis and it can therefore readily follow the cable as it engages in the grooves 40 of the sheaves and travels around the sheaves. It will be noted in Fig. 1 that the radius of the sheave groove bottom is shorter than the distance between the sheave axis and the center lines of tracks T and T' and the rails 15. The difference in distance is substantially the distance between the axis of pivot bolt 27 and the end of the frame 32 of the connector so that the frame can assume a horizontal position during shifting of the car from one track to the other, such horizontal position being shown in Figs. 1, 2 and 4. When the car is traveling on the tracks T and T' the connector frame 32 will hang vertical in order to pass readily

through the cable driving mechanism but when the car is shifted between the ends of the tracks the frame assumes a more or less horizontal position in order to accurately engage in the sheave groove without binding. The frame 32 being of sheet metal will add very little thickness to the cable and consequently will not cause bumping or jumping when the connector passes through the cable drive mechanism or around the sheaves.

I do not, of course, desire to be limited to the exact construction, arrangement and operation shown as changes and modifications are no doubt possible which would still come within the scope of the invention.

I claim as follows:

1. In a tramway, the combination of two parallel track ends, a frame adapted to reciprocate transversely of said ends, a track section on said frame normally in register with one of said track ends, a sheave below said frame having a vertical pivot in a plane midway between said track ends, the radius of said sheave being a distance less than the distance from the center of the sheave to the main track centers and to the center of the frame track, a cable passing around said sheave, a car adapted to enter said frame track section from one of said track ends, a connector pivoted to said car center for vertical rotation and connected at its lower end with said cable, said connector being adapted to swing horizontally to bridge the distance between the car center and the sheave periphery and to follow the cable around the sheave.

2. In a tramway system, the combination of two main track ends, a frame reciprocable transversely at said ends, a track section on said frame normally in registration with one of said main track ends, a horizontal sheave below said frame, the axis of said sheave being in a plane midway between the main track ends, a cable engaging said sheave, a car, a connector depending from said car and secured to the cable, said car being propelled by the cable onto the frame track section from one of said main track ends, said car having a combined longitudinal movement on said frame track section and lateral movement with said frame to be brought into position to enter the other main track end.

3. A cable connector for tram-cars comprising a plate having a vertical stud extending therefrom for securing the plate to a car bottom for rotation about a vertical axis, legs depending from said plate, a horizontal pivot bolt secured in said legs, a block having ears receiving said bolt, a U-shaped frame of sheet metal receiving said block between its ends and secured thereto, said block having a lower wedge surface, a block at the bottom of said frame

having an upper wedge surface, a wedge block extending through said frame between the wedge surfaces of the upper and lower blocks, a threaded stud extending from said wedge block, and a nut engaging said stud and the edge of said frame for forcing said wedge block between the wedge surfaces.

4. In a cable tramway, the combination of a track, a sheave, a cable for engaging 10 with the sheave, the radius of said sheave being less than the distance from the sheave axis to the track center, a car for the track, a connector having an upper part pivoted

to the car to swing about a vertical axis passing through the center line of the car, 15 the lower part of said connector being pivoted to the upper part to swing laterally, said lower part being secured at its lower end to the cable and being of a length to bridge the distance between the track center and the sheave periphery when the car travels around the sheave.

In witness whereof I hereunto subscribe my name this 5 day of June, A. D. 1916.

HUGH B. BROCKENBROUGH.
